UNITED STATES PATENT OFFICE.

WILLIAM KELLY AND OLAF G. OLSON, OF SEATTLE, WASHINGTON.

DESIGN FOR A FIRE-HOSE NOZZLE.

SPECIFICATION forming part of Design No. 26,358, dated December 1, 1896.

Application filed September 2, 1896. Serial No. 604,690. Term of patent 7 years.

To all whom it may concern:

Be it known that we, WILLIAM KELLY and OLAF G. OLSON, citizens of the United States, residing at Seattle, in the county of King and State of Washington, have invented and produced a certain new and original Design for a Fire-Hose Nozzle; and we do declare the following to be a full, clear, and exact description of the invention, such as will enable others skilled in the art to which it appertains to make and use the same.

Our invention relates to a new design for fire-hose nozzles; and it consists of a nozzle of the configuration and ornamentation shown in the accompanying drawing, in which we have illustrated our invention in perspective.

The leading feature of the design consists in the nozzle with annular rows of circular holes *b*, similar rows of square holes, similar rows of elliptical holes, similar rows of slits, and a flaring end *B*.

What we claim is—

The design for a fire-hose nozzle, as herein shown and described.

In testimony whereof we hereunto affix our signatures in presence of two witnesses.

WILLIAM KELLY.
OLAF G. OLSON.
